CARL F. AUSTEL, OF NEW YORK, N. Y.

Letters Patent No. 80,895, dated August 11, 1868.

IMPROVEMENT IN MACHINERY FOR PRINTING YARN.

The Schedule referred to in these Letters Patent and making part of the same.

TO ALL WHOM IT MAY CONCERN:

Be it known that I, CARL F. AUSTEL, of New York, in the county and State of New York, have invented a new and improved Machine for Printing Yarn; and I do hereby declare the following to be a full, clear, and exact description thereof, which will enable those skilled in the art to make and use the same, reference being had to the accompanying drawing, forming a part of this specification, in which drawing—

Figure 1 represents a longitudinal section of this invention.

Figure 2 is a plan or top view thereto.

Similar letters indicate corresponding parts.

This invention consists in the arrangement of a movable carriage, carrying two rollers, on which the yarn to be printed is stretched, and provided with a toothed rack, which gears into a cog-wheel mounted on the shaft of one of the printing-rollers, in such a manner that by imparting to the carriage a reciprocating motion the yarn is carried through between the printing-rollers, and the operation of printing said yarn is materially simplified.

A represents a frame, of wood or any other suitable material, on the top of which are formed two ways, *a'*, to receive the carriage B.

On this carriage are mounted two rollers, *a*, which have their bearings in standards, *b*, and which, by preference, are fluted, so that the yarn stretched on them is not liable to slip when the rollers are revolved. The distance between the rollers *a* is so adjusted that a skein of yarn stretched thereon will have sufficient tension to be prevented from slipping when the rollers are turned, and that by turning one of the rollers the other roller will also turn by the strain of the yarn itself.

The bearings of the rollers *a* are so arranged that said rollers can be readily taken out, for the purpose of putting on or removing the skeins, and, if desired, the standards *b* may be so arranged that they are adjustable on the carriage, so that the distance of the rollers can be regulated to suit the length of the skeins.

From one side of the carriage B rises a toothed rack, *c*, which meshes into a cog-wheel, *d*, mounted on the shaft of one of the printing-rollers *e,f*.

These rollers have their bearings in a bifurcated standard, *g*, which rises from the rear end of the frame A, and extends towards the front end thereof to such a distance that the carriage can be moved clear through under the printing-rollers.

The lower roller, *f*, dips into the ink-well *m*, which is secured between the lower arms of the bifurcated standard *g*, and the diameter of said roller, and its position, are such that its upper surface touches the inner surface of the yarn stretched over the rollers *a* in the carriage, while the bottom of the ink-well clears the lower strands of the yarn, as clearly shown in fig. 1 of the drawing.

The upper roller, *e*, is held down in its bearings by a yielding power, represented in the drawing by a frame composed of two long elastic arms, *h*, which are provided with feet, *i*, bearing on the axle of the roller, and which are hooked down by the catch *j*. Instead of the catch, however, a spring or weight might be substituted, or any other suitable mechanism might be employed to hold the roller *e* down in its bearings with a yielding pressure.

The two rollers *e,f* may be geared together by cog-wheels, if desired.

Each of the printing-rollers is provided with a series of ridges, *k*, those of one roller corresponding to those of the other, and these ridges are arranged according to the pattern to be produced on the yarn, and they are so adjusted that they bear on each other or on the yarn passing through between them.

By imparting to the carriage B a reciprocating motion on the frame A, the yarn is carried through between the rollers, and that portion of the yarn which comes in contact with the ridges of the printing-rollers is printed. The rollers *a* are then turned, so as to bring a fresh portion of the yarn under the printing-rollers, the carriage is again moved on the frame A, and a second portion of the yarn is printed, and so on until the yarn stretched on the rollers *a* is printed throughout its entire length.

By changing the printing-rollers, the pattern can be changed to suit taste and demand.

Having thus described my invention, what I claim as new, and desire to secure by Letters Patent, is—

The movable carriage B, carrying two rollers, *a*, and a rack, *c*, in combination with printing-rollers *e,f*, suspended in the standard *g*, substantially as and for the purpose herein shown and described.

CARL F. AUSTEL.
